CLOCK WITH DISC INDICATORS

Jules S. Worthington, 812 Chelham Way,
Santa Barbara, Calif. 93103

Filed July 29, 1969, Ser. No. 18,460

Term of patent 7 years

Int. Cl. D10—01

U.S. Cl. D42—7

FIG. 1

FIG. 2

FIG. 3

FIG. 4

FIG. 1 is a front elevational view of clock with disc indicators showing my new design, indicating the time as 12:00;

FIG. 2 is a side elevational view;

FIG. 3 is a front elevational view, indicating the time as 15 seconds after 3:00; and

FIG. 4 is a front elevational view, indicating the time as 10 seconds after 6:00.

The drawing is lined to indicate color without reference to specific colors.

I claim:

The ornamental design for a clock with disc indicators, as shown and described.
